UNITED STATES PATENT OFFICE.

RUDOLF AXMAN, OF SAN FRANCISCO, CALIFORNIA; JULIA A. AXMAN EXECUTRIX OF
SAID RUDOLF AXMAN, DECEASED.

RAILWAY-RAIL JOINT.

1,129,622.

Specification of Letters Patent.

Patented Feb. 23, 1915.

Application filed February 24, 1913. Serial No. 750,385.

To all whom it may concern:

Be it known that I, RUDOLF AXMAN, a citizen of the United States, residing at San Francisco, in the county of San Francisco and State of California, have invented new and useful Improvements in Railway-Rail Joints, of which the following is a specification.

This invention relates to improvements in railway railjoints and consists of the novel construction and arrangement of the parts.

The objects sought to be accomplished are, to produce a strong, simple and economical joint for the abutting ends of railway rails; to eliminate all screw threaded connections in the joint; and to bridge the gap between the ends of the abutting rails by a gradient bridge support which forms part of the railjoint; to prevent the rail ends creeping through the railjoint; and to prevent the joint members from separating should the securing bolts become loosened.

The invention will be hereinafter more fully set forth and particularly pointed out in the claims.

In the accompanying drawings: Figure 1 is a side elevation in perspective of a railjoint constructed in accordance with this invention. Fig. 2 is a plan view from above of the same.

Referring to the drawing, 1 designates a base plate having the longitudinal channel formed between the shoulders 2 and 3, and the tapered channel formed between the undercut flanges 4 and 5. To increase rigidity the base plate is provided with the longitudinal corrugation 6. The base plate is provided with the spike holes 7, punched near the edge in the usual manner.

40 The bases 8 of the abutting rail ends rest within the channel between the shoulders 2 and 3. This channel being narrower than the channel between the flanges 4 and 5, the joint can be assembled without having to slip the base plate onto the ends of the rails. The inner side plate 9 extends between the head and the base of the rail parallel with the web thereof in the usual manner. This plate has the lateral foot 10 resting upon the rail base and engaging the undercut flange 4.

45 The outer side plate 11 has the lateral foot 12 resting upon the rail base and engaging the undercut flange 5 which inclines toward the longitudinal center of the base

plate forming a tapered channel between the flanges 4 and 5. The inwardly extending flange 15 supports the head of the rail. The bridge 14 is formed integrally with the side plate 11 and extends upwardly to a level 60 even with the top of the rail, and the full length of the railjoint, the approaches 15' being inclined slightly for obvious reasons. It is the function of the bridge 14 to support the tread of the passing car wheels in passing over the gap 16 between the rail ends. Since the greatest wear on the bridge is opposite this gap it is reinforced by an impact block 17 of "manganese steel" or other very hard metal inlaid at this point. 70

The side plates are provided with holes coinciding with similar holes in the abutting rail ends through which the bolts 18 extend. These bolts are provided with slots through which the tapered keys 19 are driven and 75 twisted. The taper of these keys wedge the side plates together, snugly supporting the rail ends when the keys are driven tight.

One of the serious conditions to be met in a railjoint is lost motion. It is desirable that 80 all the elements entering into a railjoint be held at all times under tension with respect to each other. This is imperative because of the suddenness and magnitude of the impact of the car wheels in passing over the 85 railjoint. Because of this necessity for constant tension the slot and key-bolt construction is preferable to the usual thread and nut which is so liable to unscrew under vibration. 90

The outer side plate 11 with the tapered engagement with the undercut flange 5 is adapted to be driven into position. The taper causing a lateral wedging action against the rail. The function of this wedging is twofold, it insures a snug fit between the rails and the side plates, and also prevents "creeping" of the rail through the joint when the travel is all in one direction, as in the case of double track systems. To 100 allow for adjustment the side plate is provided with elongated holes 20 to receive the cross bolts. To lock the side plate in the jammed position the notches 21 and 22 in the base plate and the lateral foot of the 105 side plate respectively are provided. The spikes 23 are driven through these holes into the ties. When first set up the notches do not quite coincide necessitating a narrow spike. As resetting is required by wear a 110

wider spike is used each time to fill the space between the abutting sides of the respective notches. The inner plate 9 is not necessarily tapered so the notches in the lateral foot thereof coinciding with similar notches in the undercut flange 4 form a square hole just the size of the spike which is driven therethrough into the tie, securely anchoring the railjoint to the ties 10 and coöperating with the cross bolts to prevent the rail creeping through the joint.

The joint is installed as follows: The base plate is laid in position across the ends of the ties in the usual manner. The abutting 15 ends of the rails to be joined are set in position on the base plate, the base of the rail resting between the shoulders 2 and 3. The inner side plate is set into the side of the rail and slipped into the undercut groove 20 provided in the base plate for it. The outer side plate is placed in position in like manner, except that it is driven snugly into position against the taper of the undercut groove provided for it. The cross bolts are 25 put through the coinciding holes provided in the side plates and the web of the rail, the taper keys are driven tight and the narrow ends turned down, twisted or otherwise clenched to hold the tension of the side 30 plates against the rail ends. The spikes are driven into their respective holes permanently securing the railjoint to the ties, and locking the rail ends, and the side plates from "creeping" through the base plate.

Having thus described this invention what is claimed and desired to secure by Letters Patent is:—

1. An improved rail joint comprising a base plate having a longitudinal channel 40 adapted to receive a rail base and on each

side an undercut channel the outer channel being inclined with relation to the longitudinal median line of said plate, inner and outer side plates having lateral feet engaging the undercut channels, the outer plate 45 having a wedging engagement with its channel, the edges of said lateral feet and the overhanging edges of said undercut channels being provided with complementary notches and adapted to receive spikes, 50 wedging means for preventing separating movement of the upper edges of said side plates, said outer side plate being provided with an integral bridge having inclined approaches and running parallel with the top 55 and sides of the rail head.

2. An improved railjoint comprising a base plate, side plates engaging said base plate and the abutting rail ends, a bridge being formed integral with one of said side plates and running parallel with the top and side of the rail head, and having a recess in the upper edge thereof provided with undercut ends, and an impact block inlaid in said recess and having beveled ends engaging the 65 undercut ends of said recess.

3. An improved railjoint comprising side plates engaging the abutting rail ends, a bridge being formed integral with one of said side plates, and provided with a recess 70 in its upper edge having undercut ends, and an impact block having beveled ends engaging the undercut ends of said recess.

In testimony whereof I have hereunto set my hand in presence of two subscribing witnesses.

RUDOLF AXMAN.
